UNITED STATES PATENT OFFICE.

JAMES THOMAS, OF CHICAGO, ILLINOIS.

RAZOR.

1,188,221.

Specification of Letters Patent. Patented June 20, 1916.

Application filed November 13, 1914. Serial No. 671,998.

To all whom it may concern:

Be it known that I, JAMES THOMAS, a citizen of the United States, residing at Chicago, in the county of Cook and State of Illinois, have invented new and useful Improvements in Razors, of which the following is a specification.

This invention relates to improvements in razors, the object of the invention being to 10 provide an improved form of razor which may be used instead of the ordinary razor or of any of the usual forms of safety razor and which possesses advantages over all of such razors and is adapted to be used like 15 an ordinary razor and is at the same time rendered safe.

The invention consists in the construction, combination and arrangement of devices hereinafter described and claimed.

20 In the accompanying drawings:—Figure 1 is an elevation of a razor constructed in accordance with my invention and showing the guard open and disclosing the blade. Fig. 2 is a similar view of the same showing the guard extended from the handle and closed and showing the razor in condition for use. Fig. 3 is a longitudinal sectional view of the same. Fig. 4 is a transverse sectional view of the same. Fig. 5 is a detail 25 elevation of the blade showing the reverse side thereof from that disclosed in Fig. 1.

The handle 1 is of the usual construction, bifurcated to receive the guard 2. The guard is shaped like an ordinary razor blade 35 and comprises a main member 3 and a member 4. The main member has a shank 5 which is pivoted in the bifurcated end of the handle as at 6 and hence the guard, together with the blade which it carries may be 40 opened from the handle or closed therein, like an ordinary razor blade, as will be understood. The main member 3 of the guard has a flat inner side 7 and is provided at its outer end, and also at the inner end of its widened portion with flanges 8, which extend transversely from its plane or flat surface 7 and are provided in their opposing sides with channels 9. The guard member 4 corresponds substantially in shape with 45 the member 2 excepting that it is somewhat shorter and has a shorter shank 10. Said shank 10 is pivoted on one side of the shank 5 of the main member of the guard as at 11 and the ends of the broadened portion of 50 said member 4 are adapted to fit in the channels 9 when said member is closed against

the member 2 as shown in Figs. 3-4, the said channels serving to firmly hold the member 4 with its flat inner side closely opposed to the flat side 7 of the member 3. 50 The said member 3 is provided in its flat inner side with a longitudinal groove 12 which extends from end to end of the broadened portion thereof.

The blade 13 is thin and flat on opposite 65 sides and is here shown as provided with oppositely arranged straight or nearly straight cutting edges 14. The length of the blade is such that the same is adapted to be readily placed against the flat side of the 70 guard member 3 between the flanges 8, with either of its cutting edges projecting beyond the inner side of the guard and the said blade is provided on one side with a centrally arranged longitudinal tongue 15 75 which is engaged with the groove 12 to hold the blade in place between the members of the guard. The blade may be readily removed from the guard and another substituted or reversed so as to present another 80 cutting edge and in practice a number of blades will be used successively and the blades will be furnished to the trade already sharpened and honed so that no blade need ever be used on more than one person. Hence 85 while the razor may be used by barbers and others in exactly the same way as an ordinary razor, which many persons prefer, a patron of a barber shop may be assured that he will be shaved with a blade not used 90 on any other person. Hence my improved 95 razor is practically sanitary and it is obvious that it may very readily be kept clean.

Having thus described my invention, I claim:

In a device of the character described, in combination a bifurcated handle, a guard having a shank pivotally connected in said bifurcated handle, said guard being composed of two sections, said sections having the configuration of a razor blade, each of said sections having an inner substantially flat inclined surface, one of said sections being shaped so as to have its inner surface 100 spaced from the inner surface of the opposite section to provide a blade recess, one of said sections being provided with a longitudinal groove adjacent one longitudinal edge thereof, a blade having a longitudinal 105 rib substantially at a median line adapted to take into said groove each side of the blade 110

opposite said rib being of a lesser width than the relatively longer plane of the blade receiving recess, whereby to have its edge spaced from the inner edge of the recess, the shortest shank formed upon one of said sections, said first named shank having a recess in which the shortest shank is received, and transverse flanges curved at the opposite ends of the other section, said flanges providing channels in which the pivoted section is adapted to have its opposite end edges received in snug relation whereby to bring the longitudinal edges of both sections flush, the inner edges of said

flanges being formed concave and the opposite ends of the pivotal section being formed convex whereby the inter-engagement of said convex edges and said flanges will hold said pivotal sections frictionally against separation, and whereby said pivotal sections may bind against the blade. 15 20

In testimony whereof I affix my signature in presence of two witnesses.

JAMES THOMAS.
